UNITED STATES PATENT OFFICE

110,418

DESIGN FOR A BADGE OR SIMILAR ARTICLE

Philip F. La Follette, Madison, Wis.

Application May 16, 1938, Serial No. 77,238

Term of patent 14 years

To all whom it may concern:

Be it known that I, Philip F. La Follette, a citizen of the United States, residing at Madison, in the county of Dane, State of Wisconsin, have invented a new, original, and ornamental Design for a Badge or Similar Article, of which the following is a specification, reference being had to the accompanying drawing, forming part thereof.

Fig. 1 is a front elevational view of a badge showing my new design; and

Fig. 2 is a side view thereof.

The dominant features of my design reside in the representation on the face of the badge as shown in Fig. 1, it being understood that the same may be embodied in pins, placards, banners, or the like without departing from the spirit of my invention.

I claim:

The ornamental design for a badge or similar article, as shown and described.

PHILIP F. LA FOLLETTE.
